C. L. Parker

Attorney

UNITED STATES PATENT OFFICE.

HARLAN S. JILLSON, OF TURNERS FALLS, MASSACHUSETTS.

TOOL FOR COMPRESSING VALVE-SPRINGS.

1,384,958.

Specification of Letters Patent. Patented July 19, 1921.

Application filed May 22, 1919, Serial No. 298,956. Renewed December 15, 1920. Serial No. 430,987.

To all whom it may concern:

Be it known that I, HARLAN S. JILLSON, a citizen of the United States, residing at Turners Falls, in the county of Franklin 5 and State of Massachusetts, have invented certain new and useful Improvements in Tools for Compressing Valve-Springs, of which the following is a specification.

My invention relates to improvements in 10 tools for compressing valve springs so that the valves may be removed or ground.

An important object of the invention is to provide a device of the above mentioned character, which is simple in construction, 15 easy to operate, strong and durable.

Other objects and advantages of the invention will be apparent during the course of the following description.

In the accompanying drawings forming a 20 part of this specification, and in which like numerals are employed to designate like parts throughout the same:

Figure 1 is a side elevation of a device embodying my invention;

25 Fig. 2 is a plan view of the same;

Fig. 3 is a longitudinal section, taken on line 3—3 of Fig. 1;

Fig. 4 is a transverse section, taken on line 4—4 of Fig. 2; and

30 Fig. 5 is a perspective view of sleeve members.

In the drawings, wherein for the purpose of illustration is shown a preferred embodiment of my invention, the numeral 5 designates a cylinder of an internal combustion engine having an inlet or outlet port 6 adapted to be opened and closed by a valve 7, carried by a stem 8. This stem projects downwardly and is surrounded by a compressible coil spring 9, engaging a washer 10, held in place by a cotter pin 9', or the like, which may be removed, when the washer is moved upwardly sufficiently.

45 My device embodies a pair of permanently parallel rods 11 and 12, which are preferably cylindrical. These rods carry at their forward ends extensions 13, which are forked, as shown at 14. One forked portion 14 is adapted to contact with a shoulder 15, while the other forked portion is adapted to engage beneath the washer 10, as shown.

The rods 11 and 12 are provided at or near their forward ends with pairs of trunnions 16 and 17, pivoted within apertures 50 formed in the ends of pairs of links 18.

These links cross each other and are pivotally connected at their centers, as shown at 19. The links 18 form a lazy-tongs structure. The rear ends of the inner links 18 are apertured for receiving trunnion sections 20, which are semi-circular, and formed upon sleeve sections 21. The rear ends of the outer links 18 are apertured for pivotally receiving trunnions 22, formed upon the lower rod 12.

60 The upper rod 11 has its rear portion screw threaded, as shown at 24, and this screw threaded portion receives thereon an internal screw threaded operating sleeve 25, provided at its rear end with a handle 26 65 for turning the same. The operating sleeve 25, as more clearly shown in Fig. 3, is provided near its forward end with an annular groove 27, slidably receiving the coupling sleeve section 21, this coupling sleeve having a swiveled engagement with the operating sleeve.

70 It is seen that when the tool is arranged as shown in Fig. 1, upon rotating the operating sleeve 25, the same will be advanced 75 forwardly upon the upper rod 11, and this movement will expand the lazy-tongs structure, causing the jaws 13 to spread while remaining parallel. The washer 10 is moved upwardly compressing the spring 9 so that 80 the cotter pin or the like may be removed. When this is done, the valve 7 may be removed or it may be freely rotated or ground upon its seat.

85 Particular attention is called to the fact 90 that the device is not at all restricted to the use as illustrated in Fig. 1, wherein the jaws 13 are arranged exteriorly of or beneath the spring to be compressed. The device may be employed for compressing the spring, by 95 arranging the spring between the jaws 13, as these jaws may be moved either inwardly or outwardly by turning the operating sleeve 25. As the jaws 13 remain parallel, the spring may not be removed in grinding 100 or repairing the valve. The jaws 13 are adapted to be open for a considerable extent thereby providing free access between the same, and the device as a powerful leverage.

105 It is to be understood that the form of my invention herewith shown and described is to be taken as the preferred example of the same, and that various changes in the shape, size and arrangement of parts may 110

be resorted to without departing from the spirit of the invention or the scope of the subjoined claims.

Having thus described my invention, I claim:

1. A tool of the character described, comprising a pair of rods, one rod having a screw-threaded portion, a rotatable operating sleeve having screw-threaded engagement with the screw-threaded portion and provided with an annular recess, a collar rotatable within the recess, a link pivotally connected with one rod and with the collar, a second link pivotally connected with the rods and crossing the first-named link, and means to pivotally connect the links.

2. A tool of the character described, comprising a pair of rods, one rod having a screw-threaded portion, a rotatable operat-

ing sleeve having screw-threaded engagement with the screw-threaded portion and provided with an annular recess, a collar rotatable within the recess and formed in two parts and carrying coacting pivot elements, a link pivotally connected with one rod and provided with an aperture near its opposite end to receive the pivot elements and thereby retain the parts of the collar assembled, a second link pivotally connected with the rods and crossing the first-named link, and means to pivotally connect the links.

In testimony whereof I affix my signature in presence of two witnesses.

HARLAN S. JILLSON.

Witnesses:

THERESA L. AUBRY,
HENRY E. BEAUMIER.
